Primary Examiner — Messina L Smith*Assistant Examiner* — Aram Kwon*(74) Attorney, Agent, or Firm* — Nitin Kaushik(57) **CLAIM**

The ornamental design for a karaoke machine, as shown and described.

DESCRIPTION

FIG. 1 is a front perspective view of a karaoke machine, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of the karaoke machine, shown in an environment of use; and,

FIG. 10 is an enlarged view of an encircled area labeled 10 in FIG. 1.

The evenly-dashed broken line showing of the two microphones in FIG. 9 depict environmental structure that form no part of the claimed design. All other evenly-dashed broken lines depict portions of the karaoke machine that form no part of the claimed design.

The dash-dot-dash broken lines encircling portions of the karaoke machine illustrated in the enlargements form no part of the claimed design.

1 Claim, 10 Drawing Sheets(56)
